DRINKING CUP

Albert S. Yecko and Robert H. Fitzgerald,
Pittsburgh, Pa.

Application September 28, 1950, Serial No. 12,382

Term of patent 14 years

(Cl. D44—9)

To all whom it may concern:

Be it known that we, Albert S. Yecko and Robert H. Fitzgerald, citizens of the United States of America residing at Pittsburgh, in the county of Allegheny and State of Pennsylvania, have invented a new, original, and ornamental Design for a Drinking Cup, of which the following is a specification, reference being had to the accompanying drawing, forming part thereof.

We claim:

The ornamental design for a drinking cup, as shown.

ALBERT S. YECKO.

ROBERT H. FITZGERALD.
